UNITED STATES PATENT OFFICE.

EDWARD McCABE, OF GRANITE CITY, ILLINOIS.

METALLURGICAL FURNACE.

1,109,241.

Specification of Letters Patent. Patented Sept. 1, 1914.

Application filed March 13, 1914. Serial No. 824,447.

To all whom it may concern:

Be it known that I, EDWARD McCABE, citizen of the United States, residing at Granite City, in the county of Madison and State of Illinois, have invented certain new and useful Improvements in Metallurgical Furnaces, of which the following is a full, clear, and exact description, reference being had to the accompanying drawings, forming a part hereof.

My invention has relation to improvements in open-hearth and equivalent metallurgical furnaces; and it consists in the novel features of construction more fully set forth in the specification and pointed out in the claims.

In the drawings, Figure 1 is an end view of a conventional open-hearth furnace, broken away in parts and showing my invention applied thereto; Fig. 2 is a side elevation of the lower portion of the air-and-gas chamber, parts being broken away and illustrating my invention; Fig. 3 is a horizontal section on the line 3—3 of Fig. 2; Fig. 4 is a horizontal sectional detail on the line 4—4 of Fig. 1; Fig. 5 is a top plan of the jack-truck and slag-pot mounted thereon; and Fig. 6 is a side elevation of Fig. 5, with one of the wheels of the truck removed.

In the operation of the conventional open-hearth furnace a considerable portion of the slag floating on top of the charge undergoing treatment carries over the edge of the hearth into the flues or gas passages leading to the chamber communicating with the tunnel which discharges into the stack. This tunnel as well understood in the art is filled with the usual checker-work by which the heat of the outflowing gases is absorbed to be later imparted to the air which supplies the oxygen to the fuel by which the charge is smelted. The slag thus overflowing into the chamber aforesaid, in time clogs up the openings of the checkerwork of the tunnel at points adjacent the chamber, and in the prevailing practice, a section of the furnace walls must be removed or partially dismantled to gain access to the "slag pocket" or point of greatest accumulation of the slag

for the purpose of removing these accumulations so as to restore the checkerwork to its original condition; for it is obvious that the congealing and hardening of the slag will in time destroy the efficiency of the checker-work, closing up as it does the pas-

sages through which the gases and air are designed to circulate.

It is therefore the object of my invention to prevent the accumulation of the slag at the point aforesaid, suitable provision being made to catch the slag in suitable pots or receptacles as fast as it overflows from the hearth, the receptacles with their charge of accumulated slag being removed from time to time, and the slag dumped out, after which the receptacle is returned to catch fresh charges of slag.

A further object is to accomplish this desired result without the necessity of dismantling any portion of the furnace, and without admitting any air which would have the effect of cooling the furnace.

The advantages of the invention will be better apparent from a detailed description thereof which is as follows:—

Referring to the drawings, F represents a conventional open-hearth furnace having the usual smelting or treatment chamber C and hearth H.

In the present embodiment of my invention provision is made to burn oil (crude oil) in the chamber C, the oil being introduced at opposite sides of the furnace together with a proper proportion of steam (or air or both) through a burner nozzle or pipe 1 inserted through the wall of the furnace above each end of the hearth. The pipe 1 couples to a T 2 on the outside of the furnace, the arms of the T in turn being coupled to the pipes 3 and 4, respectively leading to suitable sources of oil and steam supply (not shown). The discharge end of the pipe 3 has connected thereto within the T 2 and nozzle 1, a tube 5, the portion within the nozzle 1 being spaced from the inner walls of the nozzle, whereby the steam is free to flow through the annular space around the tube 5 and through the nozzle 1, and mingle with the oil discharged from the tube, the two mixing as they emerge from the mouth of the nozzle 1, and burning in the chamber C where they are supplied with the necessary air or oxygen as well understood in the art.

Leading from the treatment chamber at each side of the hearth H, are down-take flues 6, 6, which discharge into the air-and-gas chamber 7 from the bottom of which leads the tunnel or regenerator flue 8 provided with the conventional checker-work 116

9. This tunnel is of the usual type and may be of any length (only a small portion being illustrated in Fig. 2) and as well understood in the art, the same discharges into, or communicates with, a suitable stack (not shown). In the present embodiment of my invention the checker-work 9 terminates a suitable distance rearward of the rear wall of the chamber 7 (Fig. 2) for a reason to 10 presently appear. At the bottom of each chamber 7 are built two catch basins 10, 10, separated by a dividing ridge *r*, the walls of the basins each converging toward a discharge hole or drain opening *o* which is 15 preferably directly under a flue 6, the center of the opening being in alinement with the axis of the flue. The opening *o* discharges through the roof or crown of an arched chamber or short tunnel 11 beneath 20 the basin 10, access to the chamber being had through an opening in the side wall of the chamber 7 normally closed or sealed by a door *D*. The crown of the arch of the chamber 11 is flat as shown (Fig. 2) this 25 construction being the most feasible as will presently appear.

Adapted to be run into the tunnel or chamber 11 is a wheeled truck 12 of any suitable design and construction, the truck 30 being provided with a hollow boss 13 for the reception of a jack-screw 14, the latter terminating at the top in a cluster of arms or a spider 15 adapted to receive and support a bowl or slag-pot 16. The pot 16 is 35 provided with a marginal bead 17 in which is formed an upper groove *h* for the reception of a suitable quantity of clay *m* for engagement with the roof of the tunnel 11 around the opening *o* when the jack with 40 its bowl is screwed tightly against the roof. The jack is provided with a series of sockets or openings *e* for receiving in succession the end of a bar or lever by which the jack is screwed or unscrewed.

45 The operation of the invention is substantially as follows:—During the treatment of a charge on the hearth *H*, considerable ebullition takes place, the boiling of the charge causing considerable portions of 50 the slag floating on top of the molten metal, to flow over the edges of the hearth into and down through the flues 6. This slag in part drops directly into the basin 10, or trickles down along the walls of the chamber 7 into the basin, whence it is drained 55 through the opening *o* into the pot 16. To properly place the pot 16, the operator deposits the same on the jack 14 (the pot being held by the arms 15) spreading a required amount of clay in the groove *h*, or enough clay to project above the groove. The truck 12 with its jack and slag-pot are then run into the tunnel 11 under the drain-opening *o*, the jack being screwed down to 65 allow the slag-pot with its luting of clay

m to freely pass under the roof of the tunnel. When the jack with its slag-pot are properly centered about the opening *o*, the operator unscrews the jack by inserting a lever successively into the sockets *e*, driving the jack with its slag-pot against the roof of the tunnel with sufficient pressure to cause the clay band *m* to make a tight joint with the roof of the tunnel. In other words, the truck and jack with its pot are tightly 70 jammed between the roof and floor of the tunnel, after which the door *D* is closed. The tight joint formed by the clay-band *m* prevents access of air to the drain opening *o* and prevents premature congealing of 75 the slag.

In the present embodiment of my invention I provide two basins 10 and two slag-pots for each chamber 7. It will be noticed (Fig. 2) that the edge of the inner basin (the left hand one in Fig. 2) comes beneath the rear wall of the chamber 7, and between the plane of said wall and the adjacent end of the checker-work 9. This prevents any possibility of slag dripping 80 onto the checker-work, practically all the slag being caught in the basin. As fast as one pot 16 fills with slag, the jack is loosened from the tunnel roof, the truck is wheeled out, the slag dumped out, or the 85 pot with its slag removed, and a fresh pot deposited on the jack and wheeled into the tunnel. Thus the overflow slag is taken care of by the simple means here shown and the danger of the slag plugging up and choking 90 the interstices of the checker-work 9 does not arise.

It is to be understood that the burners 1 are operated alternately, the slag overflow as a result of the ebullition, being usually on 105 the side of the hearth opposite the burner being operated. Thus in Fig. 1, assuming that the right-hand burner is being operated, the boiling over takes place on the left, the gases and slag (feathered and plain arrows Fig. 1) traversing the flues 6, 6, the slag being caught in the basins 10, 10, and the gases after leaving the chamber 7 traversing the checker-work of the tunnel 8. Of course when the right-hand burner 110 1 is active the checker-work of the corresponding tunnel or regenerator is traversed by the air which supplies the oxygen to the burner through the flues 6 on that side, the projection of the fuel from the burner nozzle 1 into the furnace chamber assisting in drawing in the air through the regenerator. When the left hand burner is active, the reverse of these operations takes place, so that it become an easy matter to place the jacks 115 and their slag-pots into position, the basins 10 under the active burner not collecting slag, and the operator having no dripping slag to contend with. By virtue therefore, of the alternate operation of the burners 120 130

which drive the slag to the opposite side of the hearth, the operator is always free to install the slag-pots under the basins temporarily out of commission. Of course, the 5 bulk of the slag is drawn through the usual tap-hole *t* with which the furnace is provided as well understood in the art, my invention tending to prevent the undesirable accumulations at the base of the chamber 7 10 of slag which boils over from the hearth.

The invention is not necessarily limited in its application to open-hearth furnaces as such. Neither do I wish to be limited to the particular means for forcing the slag-pot 16 15 into sealing engagement with the roof of the tunnel 11.

Having described my invention, what I claim is:—

1. In combination with a furnace provided with a hearth, down-take flues positioned in proximity to the hearth, a checker-work regenerator, a basin into which said flues operate to discharge overflow material from the hearth, said basin being spaced 25 from the checker-work and provided with a drain or discharge opening, and a portable slag pot movable into position beneath the opening and adapted to be forced against the bottom of the basin and form therewith 30 a seal around the opening.

2. In combination with a furnace having a treatment chamber and a hearth, a down-take flue leading from said treatment chamber in proximity to the hearth, an air-and-gas chamber in communication with said 35 down-take, a checker-work regenerator leading from the chamber, a basin beneath the down-take spaced from the checker-work and provided with a drain opening, a portable pot movable into position beneath the opening and adapted to be forced against the bottom of the basin and form therewith 40 a seal circumscribing said opening.

3. In combination with an open-hearth furnace provided with a treatment chamber and a hearth, down-take flues leading from the chamber in proximity to the hearth, an air-and-gas chamber communicating with 45

said flues, a checker-work regenerator flue or tunnel leading from the bottom of said 50 air-and-gas chamber, a pair of basins positioned at the bottom of said last mentioned chamber beneath the down-take flues and provided with drain openings, a dividing ridge separating the basins, a chamber or 55 tunnel beneath each basin opposite the drain opening thereof, and a portable pot operating in said tunnel and adapted to have its edges brought into forcible engagement with the bottom of the basin and form therewith, 60 a seal surrounding the drain opening of the basin.

4. In combination with an open hearth furnace having a treatment chamber and a hearth, and provided with alternately operable burners at opposite sides of the hearth, down-take flues leading from the treatment chamber at opposite sides and in proximity to, the hearth, an air-and-gas chamber communicating with each set of said flues, a 70 checker-work regenerator flue leading from the bottom of each air-and-gas chamber, a pair of non-inter-communicating catch-basins at the bottom of the air-and-gas chamber, positioned under the down-take 75 flues and to one side of the terminal of the regenerator, a dividing ridge separating the basins, each basin being provided with a bottom drain opening, a tunnel under each basin communicating with the basin through 80 the drain-opening, the latter penetrating the roof of the tunnel, a portable slag-pot adapted to be positioned beneath the roof of the tunnel beneath the drain opening and provided with a luting band to engage the 85 roof of the tunnel around the opening, and means for forcing the slag-pot and lute thereof into sealing engagement with the tunnel roof, the parts operating substantially as, and for the purpose set forth. 90

In testimony whereof I affix my signature, in presence of two witnesses.

EDWARD McCABE.
